ROBERT J. FORSYTH, OF JEFFERSON, OHIO.

GUARD FOR PUMP-CHAINS.

1,288,550.

Specification of Letters Patent. Patented Dec. 24, 1918.

Application filed August 31, 1917. Serial No. 189,153.

To all whom it may concern:

Be it known that I, ROBERT J. FORSYTH, a citizen of the United States, residing at Jefferson, in the county of Ashtabula and 5 State of Ohio, have invented certain new and useful Improvements in Guards for Pump-Chains, of which the following is a specification.

This invention relates to improvements 10 in guards for pump chains and more particularly to a chain holding device adapted to prevent the chain used in the pump from becoming detached from the driving sprocket over which the chain travels.

15 One of the objects of the invention is to provide a resiliently mounted guard overlying the chain and yieldably held in proximity to the chain as it passes over the wheel or sprocket so that free movement of the 20 chain will be permitted and displacement thereof from the sprocket will be prevented.

The invention also aims to provide a guard of this character that will not interfere with the free action of the chain and will be so 25 arranged that buckets may be employed in connection with the chain; the invention being adapted for use with any type of chain now commonly employed on chain pumps.

A further object of this invention is the 30 provision of a guard for pump chains which consists of comparatively few parts and is simple in construction, but durable and well adapted to withstand the rough usage to which devices of this character are ordinarily subjected.

For a full description of the invention and the advantages and merits thereof, reference is to be had to the following description and the accompanying drawings, where- 40 in is illustrated the preferred form of my invention, in which:

Figure 1 is a side elevation of a chain pump;

Fig. 2 is an enlarged fragmentary vertical 45 section;

Fig. 3 is an enlarged fragmentary vertical section taken on the line 3-3 of Fig. 1, and

Fig. 4 is an enlarged detailed section 50 taken on the line 4-4 of Fig. 2.

Referring to the drawing wherein is illustrated the preferred form of my invention, and in which like numerals of reference indicate corresponding parts throughout the

several views, the pump casing or boxing 1 55 has arranged near its top a shaft 2 upon which a wheel 3 is mounted. The wheel rim carries a plurality of forked elements 4 and the terminals of the forked portions are equally circumferentially spaced apart so 60 that they may mesh with the links of the chain 5 which is actuated for operating the pump. For rotating the shaft, in order that the pump may be operated, I have provided a crank 6 on one end of the shaft 2 at the 65 exterior of the pump casing 1. This crank is connected to a connecting rod 7 attached to a foot pedal 8 which will be actuated to place the pump in motion.

Referring particularly to Fig. 4 of the 70 drawing it will be noted that the forked elements 4 are arranged centrally on the rim of the wheel 3 and the links of the chain, when received on the forked elements have 75 portions disposed on opposite sides of the latter. To prevent the links thus engaged with the forked elements from becoming accidentally displaced I have provided the two 80 semi-circular guard plates 9 which are laterally spaced apart to form a central passage way 10. It will be noted that the guards are also slightly spaced from the circular path of the chain so that a slight space 85 intervenes between the guards and the links of the chain. This space, however, is not sufficient to permit the chain to "jump" or become disengaged from the forked elements. The space 10 permits the passage 90 of buckets if a chain having buckets is used.

For holding the guard in position I have 95 provided the supporting rods 11 which are in the form of strands of wire of relatively heavy gage. Each of these wires is provided with a coil 12 to form a spring so that the guards to which the wires are attached are resiliently supported and they are thus prevented from being broken or damaged when the chain strikes against the guards. When the pump is being operated at a high speed the chain will be held to this place and the common occurrence of the chain jumping off the driving wheel is prevented.

From the foregoing it will be observed 105 that a very simple and durable guard for pump chains has been provided, the details of which embody the preferred form. I desire it to be understood however, that slight changes in minor details of construc-

tion may be made without departing from the spirit of the invention or the scope of the claims hereunto appended:

1. In a device of the character described, the combination of a pump chain and a driving wheel therefor, a pair of guard members laterally spaced apart to provide a space around and above the said wheel at the upper half thereof, and a plurality of spring rods attached to and supporting the said guard members to yieldably retain them in position.
2. In a device of the character described, the combination of a pump chain and a driving wheel therefor, the latter having a plurality of forked elements meshing with

the chain, a pair of semi-circular guard members disposed above the said driving wheel at opposite sides of the said forked elements, the arcuate inner faces of the said guard members being radially spaced from the links of the chain, and supporting members for each guard member, the said supporting members having coils to provide a resiliency for yieldably supporting the said guard members.

In testimony whereof I affix my signature in presence of two witnesses.

ROBERT J. FORSYTH.
